DESCRIPTION

FIG. 1 is a perspective view of a first embodiment of the pipe threading die.

FIG. 2 is a first side view of the pipe threading die of FIG. 1.

FIG. 3 is a second side view of the pipe threading die of FIG. 1.

FIG. 4 is a first end view of the pipe threading die of FIG. 1.

FIG. 5 is a second end view of the pipe threading die of FIG. 1.

FIG. 6 is a front view of the pipe threading die of FIG. 1.

FIG. 7 is a rear view of the pipe threading die of FIG. 1.

FIG. 8 is a perspective view of a second embodiment of the pipe threading die.

FIG. 9 is a first side view of the pipe threading die of FIG. 8.

FIG. 10 is a perspective view of a third embodiment of the pipe threading die.

FIG. 11 is a first side view of the pipe threading die of FIG. 10.

FIG. 12 is a perspective view of a fourth embodiment of the pipe threading die.

FIG. 13 is a first side view of the pipe threading die of FIG. 12.

FIG. 14 is a perspective view of a fifth embodiment of the pipe threading die

(Continued)

FIG. 15 is a first side view of the pipe threading die of FIG. 14.

FIG. 16 is a second side view of the pipe threading die of FIG. 14.

FIG. 17 is a first end view of the pipe threading die of FIG. 14.

FIG. 18 is a second end view of the pipe threading die of FIG. 14.

FIG. 19 is a front view of the pipe threading die of FIG. 14.

FIG. 20 is a rear view of the pipe threading die of FIG. 14.

FIG. 21 is a perspective view of a sixth embodiment of the pipe threading die.

FIG. 22 is a first side view of the pipe threading die of FIG. 21.

FIG. 23 is a perspective view of a seventh embodiment of the pipe threading die.

FIG. 24 is a first side view of the pipe threading die of FIG. 23.

FIG. 25 is a perspective view of an eighth embodiment of the pipe threading die; and,

FIG. 26 is a first side view of the pipe threading die of FIG. 25.
